UNITED STATES PATENT OFFICE

HUGO RËHMANN, OF DUSSELDORF, GERMANY.

REVOLVING GRATE FOR GAS-PRODUCERS.

1,133,577.

Specification of Letters Patent. Patented Mar. 30, 1915.

Application filed September 2, 1913. Serial No. 787,755.

To all whom it may concern:

Be it known that I, Hugo RËHMANN, a subject of the German Emperor, and resident of Dusseldorf, Germany, have invented 5 certain new and useful Improvements in Revolving Grates for Gas-Producers, of which the following is a specification.

The present invention relates to improvements in revolving grates for gas producers 10 particularly to that class disclosed by my former Patent 937,466 of October 19, 1909.

It is the object of the present invention to improve the grate so as to adapt it for use with fuel which does not favor the formation 15 of clinkers or slags.

Another object in view is to improve the blast distribution in such a manner that the shaft underneath of the grate is at all times kept perfectly clear and that the air is 20 equally and uniformly distributed across the entire space of the shaft.

Instead of gas generator coal, ground coal briquets are now commonly used, the residues of which do not bake together which 25 however are hygroscopic.

In consequence of the exceedingly strong stirring action of the revolving grate according to my prior patent the flimsy ash particles constituting the residue of combustion 30 are quickly lumping together and form a dense layer especially at the inner sides of the exterior turret, facing the middle turret. Said layer is greatly impeding the introduction of air so that a non-uniform distribution of the air within the generator is caused.

The improvements of the grate according 40 to the present invention consist chiefly in the arrangement of a bridge in the shape of a saddle-roof connecting each of the exterior faces of the turrets with the middle turret. This bridge is suitably starting at the apex 45 of the outer turret and prevents a too violent stirring of the products of combustion of the brown coal briquets and thus avoids quickly lumping together. Moreover, the peculiar saddle-roof like shape of the bridge facilitates a readily sliding of the residues 50 away from the center of the generator. The blocking of the air introduction is prevented by providing only that wall of the bridge with perforations which is oppositely disposed to the direction of rotation of the generator, said perforations being shielded in 55 the well known manner. The improved construction of the grate facilitates moreover

the application of a new method of air introduction, as the air need not be introduced under the single apexes as it was the case heretofore. This manner of introducing and distributing the air has the advantage that the air distributing devices heretofore arranged within the space below the grate may be entirely dispensed with.

With the new arrangement of distributing 60 the air, the orifices of the air distributing pipe are not exposed under the grate but they are hidden in the brick walls or are guided along the same. By this construction the access to the generator shaft for the 65 purpose of making repairs is greatly facilitated. Besides, all orifices of the air distributing devices are averted from the grate in such a manner that no products of combustion can block the same.

In the accompanying drawings: Figure 1 70 is a side view of the improved grate. Fig. 2 is a plan view of the same. Fig. 3 is a section on line I—I of Fig. 2. Fig. 4 is a vertical section through an embodiment of the 75 air distributing device.

As shown in Figs. 1 to 4 the turrets *b*, *c* are mounted in a rotatable pan or basin *q* carrying also the customary producer body *p* supported in the usual way. The apexes *a* 80 of the lateral turrets *b* are connected with the middle turret *c* by a saddle-roof bridge *d*. The side *d'* facing the direction of rotation of the generator is not provided with perforations while the side *d''* which is 85 averted from said direction of rotation is provided with perforations, which are covered or shielded in the well known manner. The air can freely be distributed toward all 90 sides and a uniform distribution of the same 95 across the entrance shaft is obtained and the gas generation is greatly improved in uniformity.

I claim:

1. In a grate for gas producers, in combination, a tower-like erection arranged in the middle part of the grate plate and consisting of a plurality of stepped turrets integral with each other, a saddle-roof bridge connecting each of the outer turrets with the 100 middle turret, and means for leading a blast of air into said stepped turrets, substantially as set forth.

2. In a grate for gas producers, in combination, a tower-like erection arranged in the middle part of the grate plate and consisting of a plurality of stepped turrets inte- 110

gral with each other, a saddle-roof bridge connecting each of the outer turrets with the middle turret, and perforations in one of the walls of said bridge averted to the direction of rotation of the gas producer for leading a blast of air into said turrets, substantially as described.

3. In a grate for gas producers in combination, a central hollow revoluble tower, a plurality of stepped turrets integral therewith, a saddle-roof bridge connecting said

turrets, said saddle bridges having apertures formed therein averted to the direction of rotation of said grate, substantially as described.

In testimony whereof I affix my signature in presence of two witnesses.

HUGO RËHMANN. [L.S.]
